SAFETY SWITCH

George D. Brown and George M. Myers,
Nanty Glo, Pa.

Application March 1, 1934, Serial No. 713,594

2 Claims. (Cl. 200—2)

This invention relates to switches and more particularly to a safety switch adapted for use in mine explosive operations.

An object of this invention is to provide a switch which is adapted to be interposed in a power circuit and connected to a fuse or detonator, the switch being so constructed that the power circuit will be closed and grounded when the switch is in its normal position and the circuit 10 to the detonator will be closed and grounded.

Another object of this invention is to provide an improved switch of this kind wherein the operating members of the switch will be thoroughly insulated so that the switch can be connected to 15 flexible conductors and carried to the desired point where it may be set up and connected to the detonator by additional conductors.

A further object of this invention is to provide a switch which is so constructed that there will 20 not be a premature or accidental discharge of the fuse or detonator by reason of the interruption of contacts due to the space between the contact springs, terminals and ground bar when the switch is in its normal position.

25 The above and various other objects and advantages of this invention will in part be described and in part be understood from the following detailed description of the present preferred embodiment, the same being illustrated in the accompanying drawing wherein:—

Figure 1 is a detail top plan view of a device constructed according to the embodiment of this invention with the top removed.

Figure 2 is a transverse sectional view taken 35 substantially on the line 2—2 of Figure 1 and showing the cover in position.

Figure 3 is a diagrammatic view of the circuits within which the switch hereinafter described is interposed.

40 Referring to the drawing wherein like numerals designate corresponding parts throughout the views, the numeral 10 designates generally a casting of substantially rectangular configuration provided with an open top which is adapted to be closed by means of a cover or lid 11 hinged at one end by means of hinges 13. The housing or box 10 is provided with outwardly extending flanges 12 at each end, each having an aperture 14 therethrough so that the housing may be mounted on a suitable support. An insulating block or base 15 is positioned within the box 10 and engages the bottom of the box 10. A pair of guide members 16 constructed in the form of rectangular loops are secured as by a plate 17 to the base 15.

55 The plate 17 is attached to the base 15, and this

base 15 held against movement within the casting 10 by means of a bolt 18 which holds the device in assembled condition within the casting 10. The guides 16 are adapted to engage and guide slide bars 19 which are connected at one end 5 as by a connecting bar 20.

An upstanding or right angularly related bar 21 is secured at its lower end to the connecting bar 20 and a draw bar 22 is connected at one end to this post or upstanding member 21 and slidably 10 extends through one end wall of the housing 10, and is provided at its outer end with an eye 23. A connecting bar 24 is disposed between the slide bars 19 intermediate the ends thereof and is preferably of insulating material and holds these bars 15 19 in spaced parallel relation to each other coacting with the end member 20 in holding these bars 19 so that they will freely slide in the guide members 16. A contracting spring 25 is secured at one end to the end of the housing opposite from the draw bar 22 and the opposite end of the spring 25 is secured to the upstanding post or bar 21. In this manner, the slide comprising the members 19, 20 and 24 will be constantly urged toward one end of the housing 10, the purpose for which will 25 be hereinafter described.

A conductor 26 extends through one end of the housing 10 and is connected at one end to a contact post 27. A second conductor 28 is extended through this wall of the housing 10 and connected to a second fixed contact post 29. These conductors 26 and 28 are connected at their opposite ends to a source of current supply and constitute power conductors.

30 A bridging element or ground bar 30 is secured to the end bar 20 and is adapted to bridge the space between the two contact posts or terminals 27 and 29 so that when the switch is in its normal or inoperative position, the power circuit comprising the conductors 26 and 28 will be closed 40 or grounded.

A conductor 31 is connected at one end to a terminal or fixed post 32 and another conductor 33 is connected to another terminal or fixed post 34 which is spaced from the terminal 32, and 45 each of these terminals, as well as the terminals 27 and 29, are mounted on the base 15 within the housing 10. The terminals 32 and 34 are positioned forwardly of the connecting bar 24 and a metal contact 35 of relatively resilient construction is secured to the side of the connecting bar 24 confronting the terminals 32 and 34. The conductors 31 and 33 have their opposite ends connected to a detonator 36 which is shown diagrammatically in Fig. 3, and which is adapted to 50 55

light an explosive 37 also shown diagrammatically. By providing the two closed circuits hereinbefore described, there is no possibility of accidental discharge of the detonator 36 while the 5 workmen are preparing the explosive 37.

A resilient and movable contact 38 is secured to one of the slide bars 19 and a second resilient and movable contact 39 is secured to the other of the slide bars 19 and disposed in forwardly offset relation to the two terminals 32 and 34. The movable contact 38 confronts the terminal 32 and the movable contact 39 confronts the terminal 34. A conductor or connecting wire 40 connects the contact 38 with the terminal post 27 and a conductor 41 connects the contact 39 with the terminal 29.

In the use and operation of this switch, the casing 10 may be positioned at any desired point within the mine or exteriorly of the mine, if desired, and connected as by conductors 26 and 28 to a source of current supply. This current supply may be on at all times and will be grounded through the bridging member 30, which connects the two terminals 27 and 29 together. In this 20 position, which is the normal position of the slide, the contacts 38 and 39 will be positioned forwardly and in spaced relation to the terminals 32 and 34. By reason of the grounding of the current in the conductors 26 and 28, there 25 will be no jumping of current from the contact 38 to the terminal 32 or from the contact 39 to the terminal 34. In this position also, the bridging member 35 connects the two terminals 32 and 34. When it is desired to set off the detonator 36, the draw bar 22 is pulled, which opens the 30 circuit comprising the conductors 26 and 28 and the current will then flow from the terminal 26 through the terminal 40 and the contact 39 to the terminal 32 and then through the conductor 31 to the detonator. The current will pass on its 35 return from the detonator through the conductor 33 to the terminal 34, contact 39, conductor 41, terminal 29 and conductor 28. It is, of course, understood that the direction of the flow of the 40 current may be in either direction and the above 45 description is merely for purposes of showing the connection between the power circuit and the detonator circuit.

It is, of course, understood that various changes and modifications may be made in the details of construction and design of the above specifically described embodiment of this invention without departing from the spirit thereof, such changes and modifications being restricted only by the 50 scope of the following claims.

What is claimed is:—

1. A safety switch, comprising a base, a slide member slidable on said base, a pair of terminals secured to said base and adapted to be connected to a source of electric power supply, a terminal 5 bridging member carried by said slide member, a spring constantly urging said slide member in a position whereby said bridging member will engage said terminals, a second pair of terminals carried by the base in spaced relation to said first 10 pair of terminals, a second bridging member carried by said slide member in spaced relation to said first bridging member and engageable with said second pair of terminals when said first bridging member engages said first pair of terminals, a pair of contacts secured to said slide member and adapted to engage said second pair 15 of terminals when said slide member has been moved to disengage each of said bridging members from each pair of terminals, and flexible 20 conductors connecting said first pair of terminals with said contacts.

2. A safety switch, comprising an insulated base, a slide member comprising a pair of parallel bars connected together at one end, guide 25 means engaging the parallel bars for slidably mounting said slide member on the base, a pair of terminals secured to the base between said parallel bars and adapted to be connected to a source of electric power supply, a terminal bridging member extending between the parallel bars and engageable with the terminals, a spring constantly urging said slide member in a position whereby said bridging member will engage said terminals, a second pair of terminals disposed 30 between said parallel bars intermediate the ends thereof and in spaced relation to said first pair of terminals, a transversely extending bar connecting said parallel bars intermediate the ends thereof, a bridging member on said connecting 35 bar engageable with said second pair of terminals when said first bridging member engages said first pair of terminals, a pair of confronting contacts secured to the inner sides of said parallel bars and normally disposed in spaced relation 40 to said second pair of terminals, and conductors connecting said contacts with said first pair of terminals, said contacts engaging said second pair of terminals when said slide member is moved to disengage each of said bridging members from said pairs of terminals.

GEORGE D. BROWN.
